BOAT PROPELLER REMOVAL TOOL

Gary D. Jones, 3340 E. Washington,
Phoenix, Ariz. 85034

Filed Nov. 1, 1971, Ser. No. 194,796

Term of patent 14 years

Int. Cl. D8—05

U.S. Cl. D8—88

FIG. 1 is a perspective view of a boat propeller removal tool showing my new design;

FIG. 2 is a front view of the design of FIG. 1;

FIG. 3 is a right side view of said design with reference to FIG. 2;

FIG. 4 is a top view of said design with reference to FIG. 2; and

FIG. 5 is a bottom view of said design with reference to FIG. 2.

I claim:

The ornamental design for a boat propeller removal tool, as shown.
